UNITED STATES PATENT OFFICE.

JOHN E. SWEET, OF SYRACUSE, NEW YORK.

GOVERNOR FOR STEAM-ENGINES.

SPECIFICATION forming part of Letters Patent No. 252,276, dated January 10, 1882.

Application filed April 22, 1880. (Model.)

To all whom it may concern:

Be it known that I, JOHN EDSON SWEET, of the city of Syracuse, county of Onondaga and State of New York, have invented new and useful Improvements in Fly-Wheel Governors for Steam-Engines, &c., of which the following is a specification.

Before proceeding to a description of my invention I will remark that in most of the governors of the class known as "fly-wheel" governors a certain defect exists, and when that defect has been remedied it has been done at the expense of additional pieces. The defect mentioned is that of some unbalanced portion of the mechanism, usually the eccentric, tending to fall toward the shaft when above it and away from the shaft when below it, thus constantly disturbing the position of the eccentric and unnecessarily wearing the pivots and causing the cut-off to vary at the two ends of the cylinder. So well known and objectionable is this feature that inventors have added weights and levers to neutralize it.

My invention is intended to obviate all these objections; and the invention consists chiefly in the combination of the eccentric with a single governing weight or ball mounted on one end of a lever which is pivoted to the fly-wheel at a point in a line at, or nearly at, a right angle to another line passing through the pivot of the eccentric and the center of the shaft, and thus connecting the other end of said lever by a link to a projection on the eccentric opposite to its pivoted connection with the fly-wheel in such a manner that the weight of the ball and its lever at all times counterbalances the weight of the eccentric and its attachments, as will hereinafter appear.

Figure 1 is a side view of the device. Fig. 2 is a sectional view. Fig. 3 is a sectional view of the pivotal joint.

At A is represented the fly-wheel, upon which the eccentric, as at B, is mounted and connected by a pivot, as at C.

The actuating or governing weight is shown at D, mounted on a lever, as at E, which is pivoted to the fly-wheel at F in a line which forms a right angle, or nearly so, with a line passing through the pivot of the eccentric and the shaft of the fly-wheel, and the other end of said lever is connected by a link, as at G, to a pro-

jection, as at H, on the eccentric, so that the vibrations of the weight or ball are simultaneous with the vibrations of the eccentric, and exactly opposite to each other; consequently if 55 they are properly weighted they will counterbalance each other in whatever position the fly-wheel may be placed.

To produce the governing action, or to give the required resistance at the eccentric, a 60 spring, as at K, is mounted upon the fly-wheel, and its free end is attached by a link, as at L, to the projection on the eccentric, and thus forces the eccentric over to its extreme point of eccentricity. It is evident that this spring 65 may be attached on the opposite side of the fly-wheel, and may be connected to the lever or the actuating-weight in any other convenient manner to serve as a counter agent; and it may also be of a different form, as a spiral or volute. 70

As the joints at M M in the links which couple the end of the lever to the eccentric and the eccentric to the spring are subject to excessive pressure and slight movement, the form of joint shown in Fig. 3 has been adopted. 75

The holes in the ends of the links G and L are made larger than the pins which they embrace, and within these holes are secured flat pieces of tempered steel, N, with their working-faces at right angles to the line of pressure. 80 When the pressure is brought to bear on these links the pins are held firmly against these flat steel faces, and as movement takes place in the levers the pins roll, thus substituting rolling for sliding friction. 85

I claim—

1. In a fly-wheel governor, the combination of the eccentric with a single-acting governing weight or ball by suitable intermediate devices, whereby the gravitating action of the said governing weight is counterbalanced by the eccentric, as and for the purposes set forth. 90

2. The combination of the eccentric B, actuating and counterbalancing weight or ball D, centrally-pivoted lever E, and link G with the fly-wheel A, as and for the purposes set forth. 95

3. The combination of the fly-wheel A, eccentric B, counterbalancing weight or ball D, centrally-pivoted lever E, link G, and spring K, as and for the purpose set forth. 100

4. In a governor of the form described and having pivotal joints formed of a circular pin

or bearing resting on a plain surface, combined with the arms F and G of the governor, and the arms C and H of the eccentric, so related that a parallel motion is produced and a rolling action is given to the pins on their-bearing-surfaces, as hereinbefore set forth.

In testimony whereof I have hereunto set my

hand and seal in the presence of two subscribing witnesses.
